DESIGN FOR A PULL FOR SLIDE FASTENERS

Colin D. Barrett, Watertown, Conn., assignor to
Hookless Fastener Company, Meadville, Pa., a
corporation of Pennsylvania

Application January 24, 1936, Serial No. 60,798

Term of patent 14 years

To all whom it may concern:

Be it known that I, Colin D. Barrett, a citizen of the United States, residing at Watertown, in the county of Litchfield and State of Connecticut, have invented a new, original, and ornamental Design for a Pull for Slide Fasteners, of which the following is a specification, reference being had to the accompanying drawing, forming a part thereof.

In the drawing:

Fig. 1 is a plan view of a pull for slide fasteners showing my new design; and

Fig. 2 is a side view of the same.

I claim:

The ornamental design for a pull for slide fasteners as shown.

In testimony whereof I affix my signature.

COLIN D. BARRETT.
